CLAIM

The ornamental design for a suspended lighting fixture with two lamps, as shown and described.

DESCRIPTION

FIG. 1 is a bottom isometric view of the first embodiment of a suspended lighting fixture with two lamps of my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a bottom isometric view of the second embodiment thereof;

FIG. 9 is a front elevational view of the second embodiment thereof;

FIG. 10 is a back elevational view of the second embodiment thereof;

FIG. 11 is a left side elevational view of the second embodiment thereof;

FIG. 12 is a right side elevational view of the second embodiment thereof;

FIG. 13 is a bottom plan view of the second embodiment thereof; and,

FIG. 14 is a top plan view of the second embodiment thereof.
